UNITED STATES PATENT OFFICE.

EDWARD L. LOWE, OF MOORHEAD, MINNESOTA.

DESIGN FOR A SCRIP-STAMP.

47,602.

Specification for Design.

Patented July 20, 1915.

Application filed May 27, 1915. Serial No. 30,850. Term of patent 3½ years.

To all whom it may concern:

Be it known that I, EDWARD L. LOWE, a citizen of the United States, residing at Moorhead, in the county of Clay and State of Minnesota, have invented a new, original, and ornamental Design for Scrip-Stamp, of which the following is a specification, reference being had to the accompanying drawing, forming part thereof.

The figure is a plan view of a scrip stamp showing my new design.

I claim—

The ornamental design for a scrip stamp, as shown.

EDWARD L. LOWE.

Witnesses:

H. BACHENHEIN,
C. G. DOSLAND.
